Inc., Chicago, Ill., a corporation of Illinois

Application March 8, 1944, Serial No. 525,523

9 Claims. (Cl. 250—20)

1

This invention relates to wave-signal receiving systems and more generally to systems including superregenerative receivers which are relatively free from instability due to undesirable reflections of wave signals which are developed within the system.

In a radio receiving system comprising an antenna and a transmission line for coupling the antenna to the receiver, it is desirable to match the impedance of the antenna and also the impedance of the input circuit of the receiver to the respective characteristic terminal impedances of the transmission line to minimize reflections and to secure a maximum transfer of received signal energy from the antenna to the receiver. If the impedance of the transmission line is mismatched to the antenna, or to both the antenna and the receiver input circuit, undesirable reflections arise when a signal is being translated by the system. These reflections are serious in superregenerative-type receivers which inherently radiate strongly during operation. Even when a signal is not being intercepted by the antenna, such a system may radiate a periodic signal, since the receiver alternately fluctuates between an oscillatory and nonoscillatory state, as determined by the period of the quench voltage and the amplitude of the generated oscillations depends upon the effective noise-signal input to the receiver. The periodic signal so produced in the oscillatory circuit of the receiver, when applied to the transmission line, may develop troublesome reflected signals when mismatch conditions occur at the antenna and the receiver input terminals. These reflections, when impressed on the receiver, prevent the oscillations which occur during a quench cycle from dying out within the proper time limit, specifically, in the case where there is no desired signal input to the receiver, the generated oscillations are not attenuated below the thermal-agitation noise level before the build-up period of the next cycle of oscillations. As a result, oscillations are never entirely quenched in the manner required for proper operation and the receiver may oscillate continuously. The same type of undesirable oscillations may occur when a desired signal is being received.

Prior art wave-signal receiving systems of the foregoing type, which include in the circuits thereof one or more impedance mismatches, have provided unsatisfactory operation under some conditions. Until the disturbing impedances are effectively matched, some of these prior art systems cannot be utilized for their desired purpose

2

because of lack of stability. The matching of such impedances is somewhat complicated since it generally requires the connection and adjustment of one or more impedance-matching devices. It is desirable, therefore, to provide a receiver circuit of the general type under consideration in which some impedance mismatch of the type mentioned above can be tolerated.

It is an object of the invention, therefore, to provide a wave-signal receiving system of the type under consideration which is free from one or more of the above-mentioned disadvantages of the systems of the prior art.

It is another object of the invention to provide, in a wave-signal receiving system of the character under consideration, relatively simple means for substantially attenuating undesirable reflections which are developed therein while effectively translating desired wave signals.

It is a further object of the invention to provide in a wave-signal receiving system of the type under consideration, in which an impedance mismatch exists at the junction of the antenna system and the transmission line or at the foregoing junction and also at the junction of the transmission line and the input circuit of the receiver, means for substantially attenuating undesirable reflections resulting from the mismatch condition, thereby to provide stability in the system for received wave signals.

In accordance with the invention, a wave-signal receiving system the operation of which is relatively free from undesirable instability due to the influence therein of reflections of wave signals comprises an input circuit, a superregenerative receiving means having a quench period, and coupling means between the input circuit and the receiving means which has an effective electrical length such that the time interval required for the transmission of wave signals between the above-mentioned input circuit and the receiving means is at least an appreciable fraction of the quench period. The foregoing input circuit has an impedance which is mismatched to the impedance of the coupling means to which it is coupled, so that undesirable reflections tend to be developed in the coupling means and applied to the receiving means. The system also includes means in circuit with the coupling means for substantially attenuating the undesirable reflections to increase the stability of operation of said receiving means for received wave signals.

For a better understanding of the present invention, together with other and further objects thereof, reference is had to the following

description taken in connection with the accompanying drawing, and its scope will be pointed out in the appended claims.

In the accompanying drawing, Fig. 1 is a schematic circuit diagram of a superregenerative-type receiving system; while Figs. 2 and 3 comprise curves utilized in explaining the operation of the system of Fig. 1.

Referring now to Fig. 1 of the drawing, the system there illustrated includes an input circuit comprising an antenna system 10 having a vertical radiator 11 and a horizontal conductive element 12, the latter forming a suitable ground plane. Radiator 11 may be a quarter-wave antenna, while element 12 may comprise the metallic surface of an aircraft. The system also comprises a superregenerative-type receiver having a regenerative oscillatory circuit 13 including an electron tube 14. The frequency-determining circuit of unit 13 comprises the parallel combination of an adjustable inductor 16, a tuning condenser 17, and a condenser 18, which is shown in dotted lines for the reason that it may be comprised in whole or in part of the inherent capacitance of the circuit with which it is associated. The frequency-determining circuit is connected between the anode and the control electrode of tube 14 by condensers 20 and 21. A source of potential, indicated +B, is connected to the anode of tube 14 through a choke winding 24. A choke winding 25 and a cathode resistor 27 are connected in series between the cathode of tube 14 and ground. An adjustable bias for the control electrode of tube 14 is provided by a suitable means, such as a source 30 which is grounded at its positive terminal and connected in circuit with a voltage divider 31, the adjustable tap of the voltage divider being connected to the control electrode of tube 14 through a resistor 32 and a choke winding 34. Quench-frequency signals are applied to the control electrode of tube 14 through a coupling condenser 35 and the winding 34 from a quench oscillator 36 of conventional construction. The mid-point of adjustable inductor 16 in the frequency-determining circuit is grounded.

The system also includes coupling means between the input circuit or antenna circuit 10 and the receiving means. This coupling means has an effective electrical length such that the time interval required for the transmission of wave signals between the antenna circuit and the receiving means is at least an appreciable fraction of the quench period of the receiving means. This coupling means comprises a transmission line 38, preferably of the coaxial type, connected between the antenna system 10 and a point on the inductor 16 of the regenerative oscillatory circuit of the receiver. The inner conductor 39 of the transmission line 38 is connected to the radiator 11 and the outer conductor 40 is grounded and connected to the conductive element 12.

Because of the difficulty in providing an exact impedance match, the antenna system 10 generally has an impedance which is mismatched to the impedance of the transmission line 38 so that undesirable reflections may be developed in the transmission line and applied to the receiving means and, specifically, to the inductor 16 in the regenerative oscillatory circuit 13. The wave-signal receiving system also includes means in circuit with the coupling means for substantially attenuating the undesirable reflections to increase the stability of operation of the receiving means for received wave signals. This means comprises

an L-type resistance attenuator 41 including a resistor 42 in series with inner conductor 39 of the transmission line and the tapping point on inductor 16 in the receiver, and a shunt resistor 43 connected at one end to the common junction of resistor 42 and the tapping point and at its other end to ground.

In order to detect the modulation-signal components of the signal developed in the regenerative oscillatory circuit 13, a diode detector 45 is provided. The anode of diode 45 is connected through a coupling condenser 46 to the common junction between condenser 21 and inductor 16, while the cathode is connected to ground. A choke winding 48 and a load resistor 50, which are connected in series between the anode of the diode 45 and ground, complete the direct current path for the detector. The input circuit of a modulation-signal amplifier 51 is connected across the load resistor 50 and the output circuit of the amplifier is connected to a signal-reproducing device 52.

Considering now the operation of the receiving system and assuming for the moment that the impedance of the antenna system 10 is matched to the impedance of the transmission line 38 so that the influence of attenuator 41 may be neglected, a wave signal is intercepted by the antenna system 10 and translated by the transmission line 38 to the regenerative oscillatory circuit 13 of the receiver. Prior to the application of a received signal to the regenerative circuit 13, thermal-agitation noises and shot effect periodically produce the initiating voltages which cause oscillations to be built up, only to be quenched or suppressed at recurrent intervals by voltages of quench frequency which are supplied by the quench oscillator 36 to the control electrode of tube 14. When a received signal intercepted by the antenna system 10 is applied to the oscillatory circuit 13, the oscillations reach a much higher level and are sustained for a longer period before being quenched, thus imparting to the received signal a very high amplification. The signal output of tube 14 is applied to diode 45 where the modulation components are derived across load resistor 50 for application to amplifier 51 and, in turn, the signal-reproducing device 52.

Referring now to Fig. 2 for the purpose of considering in more detail the operation of the system when no desired signal is being received, Curve A represents the signal which is developed in the regenerative oscillatory circuit during this condition; curve B illustrates diagrammatically the quench voltage for application to the control electrode of tube 14, a rectangular wave form being selected to simplify the explanation; while curve C illustrates the variation of the receiver sensitivity with time. At approximately time t_0 the receiver has its maximum sensitivity, and noise signals originating within the receiver circuit elements cause oscillations in circuit 13 to build up to a maximum value at time t_1 , as shown by curve A. During the negative-conductance period t_0-t_1 , the quench voltage exceeds the critical level $x-x$ required for developing oscillations, while the sensitivity declines, as illustrated in curve C, to a minimum value at time t_1 . During the interval t_1-t_2 , the quench voltage is less than the critical level $x-x$, whereby oscillations in circuit 13 are suppressed. At time t_2 , the amplitude of the developed signal diminishes in the manner shown by curve A so that at time t_2 the

oscillations are substantially completely attenuated. In the positive-conductance interval t_1-t_3 , the sensitivity of the regenerative circuit is progressively increasing. After the time t_3 , the cycle of operation repeats. The oscillations indicated in curve A are impressed on the transmission line 38 and the antenna system 10 during the course of operation of the receiver and present no difficulties arising from reflections when the impedances of the antenna system and receiver are mismatched to that of the transmission line.

When the impedance of the antenna system is mismatched with respect to that of the transmission line, however, signals developed by unit 13 during a portion of the quench cycle are translated by the transmission line 38 to the antenna system 10 where a reflection occurs due to the mismatch and the reflected signals are translated by the transmission line and applied to unit 13 at a later time. At time t_1 , therefore, oscillatory signals of maximum amplitude are applied to line 38, are reflected by antenna system 10, and are impressed on the regenerative oscillatory circuit 13 at a later time. If the electrical length of the line 38 is such that the reflected oscillations are impressed on circuit 13 just before or approximately within the time interval t_2-t_3 , which interval is in the region of maximum sensitivity, oscillations in the regenerator will tend to build up to a high level, thereby providing sustained oscillations. This condition is not generally found in practice since the electrical length of the transmission line is usually shorter than for the condition assumed above. As a result, the action of quench oscillator 36, under the conditions assumed, no longer produces its desired effect and, consequently, the receiver does not fluctuate between an oscillatory and nonoscillatory condition in the superregenerative manner. Thus, where twice the time length of the transmission line 38, that is, twice the length measured in microseconds for a signal to be translated over the line, is approximately equal to one-quarter of the quench period, or the period of oscillator 36, undesirable reflections may seriously impair operation.

Consider now the operation of the system of Fig. 1 and taking into account the influence of attenuator 41 under the mismatch condition assumed above, the attenuation of the reflected signals in unit 41 is preferably sufficient to permit oscillations in the tuned circuit to be suppressed completely in the interval t_1-t_2 . Hence, oscillations in the regenerative circuit are suppressed below the noise-signal level before the next negative-conductance period of the regenerator begins, so that the superregenerative receiver functions in a satisfactory manner even though a mismatch exists which, in the absence of the attenuator, would cause it to be inoperative. While desired received signals which are intercepted by the antenna system 10 and translated through the receiver are also attenuated by the unit 41, this loss is more than offset by the beneficial effect of the attenuator 41 on undesired reflections which impair stability.

In Fig. 3 there is illustrated graphically the effect of multiple reflections on the tuned circuit of unit 13 when the input circuit 10 and the receiving means each have impedances which are mismatched with respect to the terminal impedances of the transmission line 38. For the condition illustrated, the time delay of the transmission line is short with reference to the quench period but is an appreciable fraction thereof and

it is assumed that a desired received signal is not being intercepted by the antenna system 10. Transmission lines having a time delay, for example, of the order of $\frac{1}{100}$ th or more of the quench period, are frequently utilized. By quench period is meant a quench cycle having a negative-conductance portion and a positive-conductance portion, and the latter portion may, in many cases, be of greater duration than the first-mentioned portion. Under these conditions, reflections occur at each point of mismatch, namely, at the junction of the antenna and transmission line and also at the junction of the transmission line and the unit 13. Curve D of Fig. 3 represents the periodic signals which are developed by the regenerative oscillatory circuit and applied to the transmission line 38. Shortly after the crest portions of such signals are reflected at the junction with the antenna system 10, the undesired reflected signals are impressed on the tuned circuit of the receiver. Such undesired signals disturb the manner in which the stored energy in the tuned circuit is dissipated during the period in which the original signals are being quenched. Instead of the peak oscillation dying out along the gradual slope E during the interval t_6-t_7 , the original signal thus decays in a series of echoes. The reflection of the peak oscillation and the multiple reflections resulting therefrom, which are applied to the oscillatory circuit 13, alter the performance of the tuned circuit and appear as a series of echoes G in the new envelope of the decaying oscillation during the quenching time. These echoes tend to prevent the oscillations from being completely quenched during the interval t_7-t_8 . Therefore, the oscillations may not decay below the noise level before the next regenerative negative-conductance period which begins at time t_8 . As a result, these undesired oscillations may hang over in the region of maximum sensitivity of the receiver and, under such conditions, continuous oscillations build up in successive quench periods and the receiver becomes overloaded.

Considering now the operation of the system taking into account the effect of unit 41, the impedance mismatch at the junctions, referred to above, produces multiple reflections which are substantially attenuated in unit 41. Each translation of a reflected signal in either direction through attenuator 41 results in a material attenuation. The action of this unit, therefore, quickly attenuates the reflections so that the envelope of the positive-conductance portion of curve D of Fig. 3 resembles the wave form J which is shown in dotted lines. It will be observed that the oscillations die out almost completely before the time t_7 and, hence, are below the thermal-agitation noise-signal level before the next negative-conductance period t_8-t_9 commences. This enables the receiver to operate in a normal manner to receive and reproduce desired signals intercepted by antenna 10.

Under the conditions where the receiver operates satisfactorily with an attenuation in unit 41 of, for example, three decibels for a desired received signal, the unit 41 provides an attenuation which is effectively a multiple of that amount on the reflected signals during their plurality of translations up and down the transmission line 38. Consequently, the receiver can be operated at a high gain, which gain may be many times three decibels, without instability of the type under consideration.

While there has been described what is at

present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A wave-signal receiving system the operation of which is relatively free from undesirable instability due to the influence therein of reflections of wave signals comprising, an input circuit, a superregenerative receiving means having a quench period, coupling means between said input circuit and said receiving means and having an effective electrical length such that the time interval required for the transmission of wave signals between said input circuit and said receiving means is at least an appreciable fraction of said quench period, said input circuit having an impedance which is mismatched to the impedance of said coupling means to which it is coupled so that undesirable reflections tend to be developed in said coupling means and applied to said receiving means, and means in circuit with said coupling means for substantially attenuating said undesirable reflections to increase the stability of operation of said receiving means for received wave signals.

2. A wave-signal receiving system the operation of which is relatively free from instability due to the influence therein of reflections of wave signals comprising, an input circuit, a superregenerative receiving means having a quench period, coupling means between said input circuit and said receiving means and having an effective electrical length such that the time interval required for the transmission of wave signals between said input circuit and said receiving means is at least an appreciable fraction of said quench period, said input circuit having an impedance which is mismatched to the impedance of said coupling means to which it is coupled so that undesirable reflections tend to be developed in said coupling means and applied to said receiving means, and resistance means in circuit with said coupling means for substantially attenuating said undesirable reflections to increase the stability of operation of said receiving means for received wave signals.

3. A wave-signal receiving system the operation of which is relatively free from undesirable instability due to the influence therein of reflections of wave signals comprising, an input circuit, a superregenerative receiving means having a quench period and including a regenerative oscillatory circuit, coupling means between said input circuit and said receiving means and having an effective electrical length such that the time interval required for the transmission of wave signals between said input circuit and said regenerative oscillatory circuit is at least an appreciable fraction of said quench period, said input circuit having an impedance which is mismatched to the impedance of said coupling means to which it is coupled so that undesirable reflections tend to be developed in said coupling means and applied to said regenerative oscillatory circuit of said receiving means, and means in circuit with said coupling means for substantially attenuating said undesirable reflections to prevent continuous oscillations in said regenerative oscillatory circuit and to increase the stability of operation of said receiving means for received wave signals.

4. A wave-signal receiving system the operation of which is relatively free from undesirable instability due to the influence therein of reflections of wave signals comprising, an input circuit for received wave signals, a superregenerative receiving means having a quench period, coupling means between said input circuit and said receiving means and having an effective electrical length such that the time interval required for the transmission of wave signals between said input circuit and said receiving means is at least an appreciable fraction of said quench period, said input circuit having an impedance which is mismatched to the impedance of said coupling means to which it is coupled so that undesirable reflections tend to be developed in said coupling means and applied to said receiving means, and means in circuit with said coupling means for attenuating by a predetermined small amount said received wave signals and substantially attenuating said undesirable reflections to increase the stability of operation of said receiving means for received wave signals.

5. A wave-signal receiving system the operation of which is relatively free from instability due to the influence therein of reflections of wave signals comprising, an input circuit, a superregenerative receiving means having a quench period, coupling means between said input circuit and said receiving means and having an effective electrical length such that the time interval required for the transmission of wave signals between said input circuit and said receiving means is at least an appreciable fraction of said quench period, said input circuit and said receiving means having impedances which are mismatched with respect to the impedances of said coupling means to which they are coupled so that undesirable reflections tend to be developed in said coupling means and applied to said receiving means, and means in circuit with said coupling means for substantially attenuating said undesirable reflections to increase the stability of operation of said receiving means for received wave signals.

6. A wave-signal receiving system the operation of which is relatively free from instability due to the influence therein of reflections of wave signals comprising, an input circuit, a superregenerative receiving means having a quench period, coupling means between said input circuit and said receiving means and having an effective electrical length such that the time interval required for the transmission of wave signals between said input circuit and said receiving means is substantially less than said quench period but is at least an appreciable fraction of said quench period, said input circuit and said receiving means having impedances which are mismatched with respect to the impedances of said coupling means to which they are coupled so that undesirable multiple reflections tend to be developed in said coupling means during each quench period and applied to said receiving means, and means in circuit with said coupling means for substantially attenuating said undesirable multiple reflections to increase the stability of operation of said receiving means for received wave signals.

7. A wave-signal receiving system the operation of which is relatively free from instability due to the influence therein of reflections of wave signals comprising, an input circuit for received wave signals, a superregenerative receiving means having a quench period, coupling means

between said input circuit and said receiving means and having an effective electrical length such that the time interval required for the transmission of wave signals between said input circuit and said receiving means is at least an appreciable fraction of said quench period, said input circuit and said receiving means having impedances which are mismatched with respect to the impedances of said coupling means to which they are coupled so that undesirable reflections tend to be developed in said coupling means and applied to said receiving means, and means in circuit with said coupling means for attenuating by a predetermined amount said received wave signals and attenuating said undesirable reflections effectively a multiple of said predetermined amount to increase the stability of operation of said receiving means for received wave signals.

8. A wave-signal receiving system the operation of which is relatively free from undesirable instability due to the influence therein of reflections of wave signals comprising, an antenna, a superregenerative receiving means having a quench period, a transmission line between said antenna and said receiving means and having an effective electrical length such that the time interval required for the transmission of wave signals between said antenna and said receiving means is at least an appreciable fraction of said quench period, said antenna and said receiving means having impedances which are mismatched with respect to the impedances of said transmission line to which they are coupled so that undesirable reflections tend to be developed in said transmission line and applied to said receiving means, and means in circuit with said transmis-

sion line for substantially attenuating said undesirable reflections to increase the stability of operation of said receiving means for received wave signals.

- 5 9. A wave-signal receiving system the operation of which is relatively free from undesirable instability from the influence therein of reflections of wave signals comprising, an antenna, a superregenerative receiving means having a quench period, a transmission line between said antenna and said receiving means and having an effective electrical length such that the time interval required for the transmission of wave signals between said antenna and said receiving means is at least an appreciable fraction of said quench period, said antenna and said receiving means having impedances which are mismatched with respect to the impedances of said transmission line to which they are coupled so that undesirable reflections tend to be developed in said transmission line and applied to said receiving means, and series resistor means and shunt resistor means in circuit with said transmission line for substantially attenuating said undesirable reflections to increase the stability of operation of said receiving means for received wave signals.
